U.S. Appl. No. 29/423,901, filed Jun. 6, 2012, First Named Inventor: Richard Mille.

* cited by examiner

Primary Examiner — Lucy Lieberman(74) *Attorney, Agent, or Firm* — Donald J. Ranft; Collen IP(57) **CLAIM**

The ornamental design for a watch, as shown and described.

DESCRIPTION

FIG. 1 is a front right perspective view of a watch showing my new design;

FIG. 2 is a rear left perspective view thereof;

FIG. 3 is a right side view thereof;

FIG. 4 is a left side view thereof;

FIG. 5 is a bottom view thereof;

FIG. 6 is a top view thereof;

FIG. 7 is a front view thereof; and,

FIG. 8 is a rear view thereof.

The broken lines are used in FIGS. 2, 5 and 6 to show portions of the watch that do not form part of the claimed design.
